UNITED STATES PATENT OFFICE.

VINCENT BENDIX, OF CHICAGO, ILLINOIS.

ENGINE-STARTER.

Specification of Letters Patent. Patented Aug. 6, 1918.

1,274,370.

Application filed October 12, 1916. Serial No. 125,293.

To all whom it may concern:

Be it known that I, VINCENT BENDIX, a citizen of the United States, residing at Chicago, in the county of Cook and State of Illinois, have invented certain new and useful Improvements in Engine-Starters, of which the following is a specification.

My invention relates to a starter for an engine such as a gas engine, and the object thereof is to provide a simple, efficient and reliable device of this character to be operated by a prime mover of any kind, such for instance as an electric motor.

My starter embodies as a material part of its organization that type of drive or transmission exemplified in patents heretofore issued to me, for instance Patent No. 1,125,935, dated January 26, 1915, and Patent No. 1,172,864, dated February 22, 1916. This type of engine starter is characterized by a prime mover (such as an electric motor or motor generator of the two unit and single unit starter systems respectively,) and a transmission or drive for transmitting the power of the motor by means of a rotatable member, such as a screw shaft, and a driving member such as a pinion mounted thereon, for transmitting the power of the motor to some member or part of the engine to be started, such as the fly-wheel thereof.

The object of my present invention is to provide a transmission or drive of the general character described, driven either by a starting motor unit or by a motor generator, constructed and arranged to automatically mesh and demesh an auxiliary gear or pinion with the fly wheel gear or other member of the engine. This special drive is, however, more particularly intended for use in connection with a motor-generator set in which a constantly rotating condition of armature shaft is presented. As shown, this special transmission embodies a regular standard construction of Bendix transmission or drive and in addition a certain operating connection between that pinion and the fly-wheel of the engine. Briefly speaking, this operating connection consists of a separate or auxiliary pinion or gear which is operated and controlled by the pinion of the screw shaft for the purpose of meshing and demeshing the auxiliary pinion as respects the fly-wheel.

In the accompanying drawings Figure 1 is a sectional elevation on the line 1-1 of Fig. 2, looking in the direction of the arrow;

Fig. 2 a section on the line 2-2 of Fig. 1, Fig. 3 a section of a modified form of construction; Fig. 4 an elevation of one side of the pinion 12; and Fig. 5 an elevation of the spring retainer 15.

The construction and mode of operation of the standard Bendix drive embodied in the organization about to be explained are the same as that illustrated in my patents aforesaid. It will therefore be sufficient to merely designate the parts by reference numerals as follows: 1 is the armature shaft, 2 is the hollow screw shaft thereon, 3 the pinion or gear screw-threaded on the screw-shaft and 4 the spring driving connection between the outer end of the shaft 1 and the driving head 2^a. A portion of the casing of the motor is indicated at A. This motor may be either a single unit or a motor generator.

The new or additional portion of this new organization of transmission or drive comprises essentially a pinion or gear operated and controlled in its movements, both rotary and longitudinal, by the pinion 3 of the standard drive, whereby such additional pinion is adapted to be meshed with and demeshed from the gear teeth 5^a of a fly wheel 5 or other rotatable part of the engine to be started.

Describing this additional or operating connection between the pinion 3 and the fly-wheel of the engine, the same comprises a stationary shaft 6 mounted at one end in the boss a of the motor casing and in a bracket 7, such shaft being preferably held against rotation and longitudinal movement by a pin 8 passing through such shaft, bushing 9 and bracket 7. On this shaft is mounted, for both rotary and longitudinal movement, an auxiliary or second pinion 10 which is in such position as to become meshed with the pinion 3 when the latter advances longitudinally on its screw shaft 2 when the motor is started, as hereinafter explained. This pinion 10 is also adapted when moved longitudinally along the shaft 6 to mesh with the teeth 5^a of the fly-wheel as indicated by the dotted lines.

The pinion 10 is provided on one side with a cylindrical extension 11 having a reduced middle portion 11^a and end flanges or shoulders 11^b and 11^c respectively. Within this reduced portion 11^a a part or projection of the pinion 3 is adapted to move and to cooperate with said shoulders 11^b and 11^c, in

the present instance the weight disk 3^a being utilized for this purpose.

Describing the operation of this transmission or drive, the standard transmission 5 operates in the usual way except that the pinion 3 does not mesh directly with the fly-wheel as in my patents aforesaid, but meshes with the pinion or gear 10 and also in its movement longitudinally of the screw shaft 10 bodily moves or slides the pinion 10 to the left, Fig. 2, into mesh with the fly-wheel teeth, as shown in dotted lines. This sliding of the pinion 10 is caused by the contact of the weight disk 3^a against the shoulder 15 11^b. After the engine has started on its own power and the pinion 3 has moved back to normal or home position, this weight disk after traversing the length of the reduced portion 11^a will contact the shoulder 11^b and 20 demesh the pinion 10 from the fly-wheel and retract it to normal position, as shown in full lines in Fig. 2.

In case the teeth of pinions 3 and 10 should abut end to end, the pressure is relieved by the compression action of the spring 4 while these pinions are being brought into mesh. In like manner, the pressure is relieved in case the teeth of pinion 10 and the fly wheel should abut end to 30 end.

In this manner and by these means the transmission or drive is entirely automatic throughout, inasmuch as the starting of the electric motor automatically causes the 35 meshing of the pinions and the starting of the engine, and the starting of the engine on its own power causes a demeshing of said pinions. Also, this transmission is applicable to a motor-generator set in which the 40 armature shaft and consequently the screw shaft are constantly rotating when the engine is running. It is evident that this construction of transmission may be utilized in connection with a single motor unit as a reduction gearing by employing the proper 45 gear ratios between the pinions 3 and 10.

In Figs. 3, 4 and 5 I have shown a modified form of construction according to which the auxiliary pinion is controlled by the 50 regular pinion only as to its meshing operation with respect to the fly wheel, separate means being provided for returning the auxiliary pinion to home or normal position. The corresponding parts in Figs. 2 and 3 are 55 given the same reference characters. In this modification the auxiliary pinion 12 which preferably has in its central bore a bushing 13 is adapted to rotate and to slide longitudinally upon the shaft 6. This pinion is held to its right-hand or normal position shown in Fig. 3 with a yielding pressure, as by means of the coiled spring 14, one end of which is received within the circular groove 12^a of the auxiliary pinion and 60 the other end within the groove 15^a of a

spring retainer 15. This retainer is made of sheet metal having a central opening so as to fit upon and be centered by the shaft 6. This spring holds the auxiliary pinion outwardly toward the right, Fig. 3, against the 70 edge of a sleeve 16 acting as a stop therefor, such sleeve pressing in turn against the bushing 9.

The two pinions 3 and 12 are relatively so mounted that when the pinion 3 is advanced inwardly toward the motor, due to rotation of the screw shaft, it will mesh with the pinion 12 and after full meshing of these two pinions has taken place the weight disk 3^a of the pinion 3 will come into contact with the right-hand side of the pinion 12, with the result that the latter pinion will be moved longitudinally of its axis and along the shaft 6 against the tension of the spring 14 and into mesh with the teeth of the fly wheel. When the pinion 3 has reached its outermost position toward the left, Fig. 3, when it can no longer move longitudinally, but must rotate with the shaft, it will rotate the pinion 12 and consequently rotate the fly 85 wheel. When the engine starts on its own power and the pinion 3 moves backwardly along the screw shaft to home position, the pinion 12 being thereupon relieved of the pressure holding it to the left against the 90 tension of the spring will move back to its home position, thereby becoming demeshed from the fly wheel.

I claim:

1. In a drive of the character described, 100 the combination of a rotatable member, a driving member mounted thereon for rotary movement therewith and longitudinal movement thereon, and a second driving member which is operated and controlled by the first 105 driving member and which is adapted to be thereby operatively engaged with a part of the engine to be started.

2. In a drive of the character described, 110 the combination of a rotatable screw shaft, a pinion screw threaded thereon for rotary movement therewith and longitudinal movement thereon, and a second pinion which is adapted to operatively engage a part of the engine to be started and with which the first 115 pinion is adapted to mesh when the screw shaft is rotated.

3. In a drive of the character described, 120 the combination of a rotatable screw shaft, a pinion screw threaded thereon for rotary movement therewith and longitudinal movement thereon, and a second pinion which is adapted to operatively engage a part of the engine to be started and with which the first 125 pinion is adapted to mesh when the screw shaft is rotated, said second pinion being arranged in the path of longitudinal movement of the first pinion and adapted to be thereby moved longitudinally.

4. In a drive of the character described, 130

the combination of a rotatable screw shaft, a pinion screw threaded thereon for rotary movement therewith and longitudinal movement thereon, and a second pinion which is 5 adapted to operatively engage a part of the engine to be started and with which the first pinion is adapted to mesh when the screw shaft is rotated, said first pinion having operative connection with the second pinion for 10 moving the latter longitudinally in both directions.

5. In a drive of the character described, the combination of a rotatable screw shaft, a pinion screw threaded thereon for rotary 15 movement therewith and longitudinal movement thereon, and a second pinion which is adapted to operatively engage a part of the engine to be started and with which the first pinion is adapted to mesh when the screw 20 shaft is rotated, said first pinion having a projection adapted to engage the second pinion and move it longitudinally.

6. In a drive of the character described, the combination of a rotatable screw shaft, a 25 pinion screw threaded thereon for rotary movement therewith and longitudinal movement thereon, and a second pinion which is adapted to operatively engage a part of the engine to be started and with which the first 30 pinion is adapted to mesh when the screw shaft is rotated, said first pinion having at one end a projection adapted to engage the second pinion and move it longitudinally after the two pinions have meshed.

35 7. In a drive of the character described, the combination of a rotatable screw shaft, a pinion screw threaded thereon for rotary movement therewith and longitudinal movement thereon, and a second pinion which is 40 adapted to operatively engage a part of the engine to be started and with which the first pinion is adapted to mesh when the screw shaft is rotated, said first pinion having a 45 projection adapted to engage the second pinion and move it longitudinally in one direction and the second pinion having a projection adapted to be engaged by said first named projection whereby the second pinion is moved longitudinally in the other direction.

50 8. In a drive of the character described, the combination of a rotatable screw shaft, a pinion screw threaded thereon for rotary movement therewith and longitudinal movement 55 thereon, and a second pinion which is adapted to operatively engage a part of the engine to be started and with which the first pinion is adapted to mesh when the screw shaft is rotated, said second pinion having 60 an extension provided with a reduced portion forming two opposed shoulders, and the first pinion having a projection adapted to be received by such reduced portion and to coöperate with said shoulders.

65 9. In a drive of the character described,

the combination of a rotatable screw shaft, a pinion screw threaded thereon for rotary movement therewith and longitudinal movement thereon, and a second pinion which is 70 adapted to operatively engage a part of the engine to be started and with which the first pinion is adapted to mesh when the screw shaft is rotated, said second pinion having an extension provided with a reduced portion 75 forming two opposed shoulders, and the first pinion having a projection adapted to be received by such reduced portion and to coöperate with said shoulders and the first pinion having at one end a disk projecting beyond the outer edge of the pinion 80 teeth and adapted to coöperate with said shoulders.

10. In a device of the character described, the combination of a rotatable screw shaft, a pinion screw threaded thereon for rotary 85 movement therewith and longitudinal movement thereon, a plain shaft parallel to the screw shaft, a second pinion mounted to rotate and to slide loosely thereon, said second pinion being located in a position to be 90 meshed with the first pinion when the latter moves longitudinally of the screw shaft.

11. In a drive of the character described, the combination of a driving shaft, a rotatable member driven thereby, a driving 95 member mounted on the rotatable member for rotary movement therewith and longitudinal movement thereof, a shaft parallel to the driving shaft, and a second driving member which is mounted on the second- 100 named shaft and operated and controlled by the first-named driving member, and which is adapted to be thereby operatively engaged with a part of the engine to be started.

12. In a drive of the character described, the combination of a driving shaft, a screw 105 shaft driven thereby, a driving member mounted on the screw shaft for rotary movement therewith and longitudinal movement thereof, a shaft parallel to the driving shaft, 110 and a second driving member which is mounted on the second-named shaft and operated and controlled by the first-named driving member, and which is adapted to be thereby operatively engaged with a part of 115 the engine to be started.

13. In a drive of the character described, the combination of a driving shaft, a hollow screw shaft encircling the driving shaft and driven thereby, a driving member mounted 120 on the screw shaft for rotary movement therewith and longitudinal movement thereof, and a second driving member which is operated and controlled by the first driving member and which is adapted to be thereby 125 operatively engaged with a part of the engine to be started.

14. In a drive of the character described, the combination of a driving shaft, a hollow screw shaft encircling the driving shaft and 130

4
driven thereby, a pinion screw-threaded on the screw shaft for rotary movement therewith and longitudinal movement thereof, and a second pinion which is operated and controlled by the first pinion and which is adapted to be thereby operatively engaged with a part of the engine to be started.

15. In a drive of the character described, the combination of a motor-driven member 10 mounted for automatic longitudinal move-

ment when the motor is operated, and a driving member mounted for rotary and longitudinal movement and, when moved longitudinally, adapted to be engaged with a part of the engine to be started, said 1 driving member being so moved longitudinally by the first-named member in its longitudinal movement.

VINCENT BENDIX.
